STABILIZING MATERIAL INTRODUCING DEVICE

John Robbins Rushmer, Amarillo, Tex.

Application December 31, 1942, Serial No. 470,891

1 Claim. (Cl. 61—36)

My invention relates to a device more especially adapted for the introduction of suitable liquid borne material into the ballast beneath railroad tracks; the device being intended for use with a method of pressure grouting whereby the grout or material is properly introduced into or beneath the previously laid ballast underneath the railroad tracks.

The invention has for its object the provision of a device which may be readily inserted or driven into or through the ballast, with the upper end of the device preferably provided with a suitable driving head, while the lower end, at pre-arranged distances from the driving point, is provided with outlet or discharge openings arranged at a predetermined point relative to each other and preferably at a predetermined angle relative to the longitudinal axis of the device; while the device adjacent the upper end is provided with an inlet or coupling for making connection with a suitable supply source of grout, slurry or other liquid borne earthy materials, including Portland or other cements and/or bitumen in one or more forms; the inlet or coupling and the discharge openings preferably having a definite relation with each other so as to determine the direction of discharge of the grout relative to the tracks.

The objects and advantages of my invention will be readily comprehended from the detailed description of the accompanying drawing wherein:

Figure 1 is a cross-sectional elevation of a railroad track with a pair of my improved devices shown in grout introducing position.

Figure 2 is a longitudinal sectional view of my improved device with an intermediate portion broken away.

Figure 3 is a cross-sectional view taken on the line 3—3 of Figure 2 looking in the direction of the arrows.

My device is intended for the injection or introduction of a suitable solidifying material into the sub-soil of a structure, being more especially intended for the introduction of grout or other liquid borne and quick setting material into the base of the ballast and into the voids or pockets beneath the ties of railroad tracks, in order that proper solidification or stabilization of a railway roadbed may be obtained.

The specific exemplification of the invention illustrated in the drawing consists of a suitable metal tubing 10, preferably seamless steel of proper diameter, and of variable length, provided adjacent its lower end with a pair of outlet open-

ings as at 11, 11, arranged at opposite sides of the longitudinal axis of the tubing and in staggered relation or at different distances from the lower end of the tubing, as shown in Figure 2. The outlet openings 11, 11, as shown in Figure 2, are preferably arranged at an inclination relative to the longitudinal axis of the tubing, sloping inwardly toward the lower pointed end of the tubing in such manner that foreign material, such as ballast, rocks, etc., will have a tendency to roll away from the holes, rather than into the tubing when the pointed end is driven into the ballast, and thus ensure a freer outward flow or discharge of the solidifying or stabilizing material. In order that the tubing may be readily driven into or through the ballast, indicated at 12 in Figure 1, and also prevent ingress of foreign material, I provide the lower end of the tubing with a pointed steel insert 13 whose outer surface preferably is faced with a hard welding rod as at 14 which follows the taper of the steel insert 13 and shoulders the lower end of the tubing 10.

The upper end of the tubing 10 is provided with a driving head 15 preferably consisting of a solid steel block, bored at one end to receive the upper end of the tubing 10, with the lower end of the steel block welded to the tubing 10 by the fillet 16; while the upper end of the block preferably is faced with a hard welding rod, as at 17, to prevent deformation of the block by hammer blows in the driving operation. One side of the driving head 15 and of the inserted upper end of the tubing 10 are bored at a downward inclination as at 18, Figure 2, and the driving head coincident with the bore 18 is provided with a pipe coupling 19, preferably arranged at the same inclination as the bore 18; the interior of the pipe coupling being shown threaded to receive a conduit or hose leading from a source of stabilizing material which preferably is under a certain degree of pressure.

The inlet coupling 19 is shown welded, at 20, to the tubing 10; and the coupling 19 is preferably arranged on the same side of the device as one of the outlet or discharge openings 11, being in the same longitudinal plane, thus enabling the operator to determine the directional position of the outlets 11 and direction of discharge of the grout or liquid borne material.

Railway roadbeds beneath the ballast 12 frequently develop voids or pockets, as indicated at 21 in Figure 1, and when these voids or pockets develop beneath the rail supporting members or ties 22, the latter become depressed by the weight

of passing trains, causing unevenness in the track and unequal strains on the rails and adjacent ties.

When these voids develop in the sub-structure beneath the ties, it is essential to introduce a suitable solidifying material or grout—such as cements and/or certain forms of bitumen, or other suitable liquid borne earthy materials—into the voids or pockets without disturbing the impacted ballast.

With my improved device, this may be readily accomplished by forcing or driving the pointed end 13 of the device through the ballast and into the void or pocket—the length (which may be variable) of the device enabling the lower ported portion to extend into the voids in the sub-structure so as to discharge the quick setting material (which is preferably under pressure) into the pockets or voids, while the upper end of the device is disposed above the ballast to permit connection to be made between a suitable source of stabilizing material and the inlet coupling 19, as illustrated in Figure 1, where a pair of the devices are shown, at opposite sides of the track, driven into the cavities or voids 21 beneath the normal plane of the ballast 12.

The invention has been described as especially applicable for use in the stabilization of the ballast of railway tracks, but it is apparent that the device is equally well adapted for use in stabilizing and solidifying other types of sub-structures;

the specific exemplification of the invention being believed to be the best embodiment which has been described in terms employed for purposes of description and not as terms of limitation as structural modifications may be possible without, however, departing from the spirit of my invention as defined in the appended claim.

What I claim is:

A device of the character described comprising 10 a steel tubing provided in its side adjacent its upper end with an inwardly sloping inlet opening and adjacent its lower end and on opposite sides of its longitudinal axis with straight rearwardly sloping outlet openings arranged in staggered relation, with one of said outlet openings arranged on the same side of the tubing as said inlet opening; a pointed steel insert arranged in and closing the lower end of said tubing beyond said outlet openings, the outer pointed end of said insert being faced with a hard welding rod providing an abutting shoulder for the end of the tubing; an elongated driving head longitudinally bored at its lower end to receive and to close the upper end of said tubing and welded thereto, the side of the bored end of said head having an upwardly sloping opening communicating with the sloping inlet opening in said tube; and an upwardly sloping inlet coupling intimately secured to said head about the side opening therein.

JOHN ROBBINS RUSHMER.
